TOY BULLDOZER

Robert Genin, Scarsdale, N.Y., assignor to Child Guidance Toys, Inc., New York, N.Y., a corporation of New York

Filed Apr. 5, 1967, Ser. No. 6,530

Term of patent 14 years

(Cl. D34—15)

FIG. 1 is a perspective view of my design for a toy bulldozer having a transparent body;

FIG. 2 is a side view of the toy bulldozer, the internal gears thereof being visible through the transparent body; and

FIG. 3 is a front view of the toy bulldozer.

The dominant features of my design reside in the combination, on the toy bulldozer disclosed, of the particular grill and exhaust stack configurations, together with the visible gear train within the transparent body portion, all as shown.

I claim:

The ornamental design for a toy bulldozer, substantially as shown and described.
